HEAT INSULATING PAD

Lida McKittrick, Los Angeles, Calif.

Application March 4, 1935, Serial No. 9,242

4 Claims. (Cl. 65—61)

This invention relates to a pad adapted to be placed between hot dishes and a table top, to protect the table top from the heat of the dishes.

Such pads are now in common use, and usually comprise a flat member made from heat insulation material such as felt or asbestos, or a combination of superimposed layers of this type of material. The hot dish in this well-known form, is merely placed upon the pad. The hot dish however, may be a large platter, a small plate, or a percolator or tea pot, having different areas of contact. Accordingly, pads of this well-known type are usually made in a number of sizes, and the housewife usually requires an ample range 15 of sizes of pads.

Of course, several smaller pads could be used, spread about over the table top, to accommodate a large dish; but such an arrangement is obviously not very effective. The dish can readily slide 20 off the pads; and, even when an adequately large pad is used, there is always danger that in moving the dish around on the table, the pad will be forgotten, and the dish will be placed directly on the table top.

It is one of the objects of this invention to obviate these disadvantages, and particularly by ensuring that once a pad or pads are used with a dish, the pad or pads remain in place on the bottom of the dish.

This result is accomplished by providing a device whereby the pad is detachably adhered to the dish, so that wherever the dish is moved, the pad stays thereon.

It is another object of this invention, therefore, to furnish a pad having provisions for ready attachment and removal thereof with respect to the dish.

When so arranged, a pad of this character can be used with a small dish, or several small pads 40 can be used with a larger dish, with the assurance that the table will always be adequately shielded against injury and without danger of displacement between the pad and the dish.

This invention possesses many other advantages, and has other objects which may be made more easily apparent from a consideration of several embodiments of the invention. For this purpose there are shown several forms in the drawing accompanying and forming part of the present specification. These forms shall now be described in detail, illustrating the general principles of the invention; but it is to be understood that this detailed description is not to be taken in a limiting sense, since the scope of the invention 50 is best defined by the appended claims.

Referring to the drawing:

Figure 1 is a sectional view of a pad embodying the invention, shown as in cooperative relation with the bottom of a dish or pan having a recess 5 therein;

Fig. 2 is a top plan view of the pad, partly in section; and

Fig. 3 is a pictorial view of a modified form of the pad, partly in section.

In the present instance, the pad 1 is shown as 10 of circular form, having a top covering 2 and a bottom covering 3, and a central square of rectangular opening 4. It is understood of course that the pad 1 can be made in any desired manner, as for example a plurality of layers of heat 15 insulation material or the like; such as asbestos, felt, cardboard, etc.

The hot dish or plate 5 is shown in this instance as having a recess 6 and as resting upon the pad 1. In order to attach the pad 1 to the 20 bottom of the dish 5, use is made of a detachable vacuum producing means, such as a vacuum cup 7. This vacuum cup 7 can be made of soft rubber. It can be pressed into place as illustrated in Fig. 1, thereby holding the pad 1 detachably to 25 the bottom of the plate or dish. The cup 7 can be so arranged that its contacting suction surface can be raised or projected above the top surface of the pad 1. In this way, the cup 7 can be pressed upwardly into the recess 6 in case there 30 is such a recess in the bottom of the hot dish or plate 5. If no such recess is formed, the necessity of projecting the cup 7 is obviated.

In order to hold vacuum cup 6 yieldingly or resiliently with respect to the pad 1, use is made of 35 a resilient wire 8 such as spring steel. This wire 8 has a loop 9 arranged resiliently to press into a groove 10 formed in the extension 11 of the cup 7. The wire 8 can furthermore have a series of convolutions so as to increase its flexibility. 40 The ends of the wire are formed in substantially semi-circular extensions 12 and 13, embedded in the pad 1, as by being placed underneath the top covering 2. These extensions 12 and 13 form substantially a complete circle, and serve to hold 45 the structure including the wire 8 and cup 7, resiliently in place in the center of the opening 4.

In using the pad 1, it is placed against the bottom surface of the dish or plate 5. If the dish or plate has no recess, the cup 7 is merely pressed 50 against the bottom of the dish or plate to hold the pad 1 detachably in place. The dish or plate can then be transported at will, and the pad 1 will stay attached to the plate 5. Removal of the pad 1 is comparatively simple, as the cup 7 can be 55

5 pulled outwardly to relieve the suction. If the bottom of the plate or dish 5 is provided with a recess such as 6, the cup 7 is projected upwardly above the pad 1 so as to contact with the surface of the recess as illustrated in Fig. 1.

The wire 8 is preferably made of spring material so that the normal position of the vacuum cup 7 corresponds substantially with the top surface of pad 1.

10 10 The vacuum cup 7 is readily assembled with the wire 8 as by twisting the straight portions of the wire structure 8 immediately adjacent the loop 9. This will cause loop 9 to open and thereby be enlarged sufficiently to permit the entry of the cup extension 11 into the loop 9.

15 In the form shown in Fig. 3, the pad 14 is made with a non-projectible vacuum cup 15. In this instance a wire or rod 16 passes entirely through the boss 17 of the vacuum cup 15, and is thereby retained in the central aperture of the pad 14. The wire or rod 16 is held securely in place as by being embedded in the pad 14.

I claim:

1. In a pad device upon which a dish or the like 25 is adapted to rest, a body portion having an aperture, a vacuum cup for detachably connecting the pad to the bottom of the dish or the like, and yielding supporting means for the cup, joining it to the pad, comprising a wire connected to the 20 cup and having oppositely extending convolutions, the ends of the wire being non-radial to the axis of the cup and embedded in the pad body for a considerable distance.

2. In a pad device upon which a dish or the

like is adapted to rest, a body portion having an aperture, a vacuum cup for detachably connecting the pad to the bottom of the dish or the like, and yielding supporting means for the cup, joining it to the pad, comprising a wire connected to the 5 cup and having oppositely extending convolutions, the ends of the wire being formed to correspond in general to the edge of the pad body, and being attached to the pad body near its edge.

3. In a pad device upon which a dish or the like 10 is adapted to rest, a body portion having an aperture, a vacuum cup for detachably connecting the pad to the bottom of the dish or the like, and yielding supporting means for the cup, joining it to the pad, comprising a wire connected to the 15 cup and having oppositely extending convolutions, said convolutions extending generally in a direction perpendicular to the axis of the cup, the ends of the convolutions being attached to the pad.

4. In a pad device upon which a dish or the like 20 is adapted to rest, a body portion having a large central aperture, a vacuum cup for detachably connecting the pad to the bottom of the dish or the like, and resilient means for supporting the cup with respect to the pad body, said yielding 25 means including a convoluted portion in the aperture and extensions embedded in the pad through the wall of the aperture, said convolutions being unimbedded and in the aperture, and extending generally in a direction perpendicular 30 to the axis of the cup, and said extensions being formed to correspond in general to the edge of the pad body.

LIDA McKITTRICK.
